UNITED STATES PATENT OFFICE

147,636

DESIGN FOR A COMBINED DESK LAMP AND
PENCIL TRAY

Carl C. Braun, Stamford, Conn., assignor to
Smith Metal Arts Company, Inc., Buffalo, N. Y.,
a corporation of New York

Application May 31, 1946, Serial No. 130,262

Term of patent 14 years

(Cl. D48—20)

To all whom it may concern:

Be it known that I, Carl C. Braun, a citizen of the United States, residing at Stamford, in the county of Fairfield, State of Connecticut, have invented a new, original, and ornamental Design for a Combined Desk Lamp and Pencil Tray, of which the following is a specification, reference being had to the accompanying drawing, forming part thereof.

Figure 1 is a front elevation of a combined desk lamp and pencil tray embodying my new design.

Figure 2 is a top plan view thereof.

Figure 3 is a rear elevation thereof.

Figures 4 and 5 are elevations of the respective ends thereof.

Figure 6 is a front perspective view thereof.

I claim:

The ornamental design for a combined desk lamp and pencil tray, as shown.

CARL C. BRAUN.
